NIELS PETER MADSEN AND JOHN AAGE GUSTAV JENSEN, OF CHICAGO, ILLINOIS, AS
SIGNORS OF ONE-THIRD TO LOUIS PLATTER, OF OAK PARK, ILLINOIS

WINDOW CONSTRUCTION

Application filed January 8, 1931. Serial No. 507,816.

This invention relates to window constructions, and has for its particular object to produce a simple, practical and efficient arrangement for guiding slidably mounted sashes in the window frame so as to frictionally hold the sashes in any raised position without the employment of means other than the sash guiding elements, and to utilize the sash guiding elements so as to obviate the necessity for equipping the window with the usual weather strips or guards. Another object is to provide means for retracting or releasing the sash guiding elements from operable engagement with the sashes, and at the same time providing against accidental dropping of the sashes when released. Further objects and advantages to be attained will hereinafter more fully appear.

The invention consists in the novel general construction and in the parts, and combinations and arrangements of parts thereof, as hereinafter described and set forth with particularity in the appended claims.

In the accompanying drawing, illustrating a practical adaptation of the invention,

Fig. 1 is a fragmentary view, in front elevation and partial vertical section, of a window equipped in accordance with the invention, and parts being broken away to fore-shorten the figure in length and breadth and yet illustrate a complete window structure;

Fig. 2 is a fragmentary vertical section, on an enlarged scale, illustrating the device for retracting the sash guiding element and for arresting the downward movement of the released sash;

Fig. 3 is a fragmentary section taken on or about the line 3—3 of Fig. 2; and

Fig. 4 is a fragmentary view in side elevation and partial vertical section, in the region of application of the retracting device for the sash guiding elements, and illustrating further details of the sash arresting member of the device.

Referring now to the drawing, the numeral 5 designates a window frame which, except for the particular details hereinafter described for the purpose of illustrating the present invention, may be of any ordinary construction and arrangement. Slidable in

the frame is an upper sash 6 and a lower sash 7, said sashes being provided with the usual glass panels or panes 8 and 9, respectively. The sashes are guided on the vertical side members or stiles 10 of the window frame by spring-pressed bars 11 which are freely slideable laterally in vertical channels 12 provided in the side frame members or stiles 10, suitable provision being made for preventing endwise movement of said bars 11.

The springs 12, a plurality of which are provided for each of the bars 11, are seated at one end in recesses 14 in the bottoms of the channels 12, and located at regular intervals throughout the length thereof, and constantly under compression, so as to normally press the bars 11 outwardly in the channels 12 and against the adjacent edge portions of the respective sashes 6 and 7. The combined strength of the springs 13 exerts a resilient pressure on the bars 11 sufficient for the purpose of normally holding sashes 6 and 7 in raised position by frictional contact or braking effect, and, preferably, the sash engaging faces of said bars 11 are provided with rounded longitudinal ribs 15 which are fitted snugly in counterpart grooves 16 provided therefor in the meeting faces of the sashes. By this provision, the necessity for providing the usual parting strip on the vertical side frame member or stile 10 is obviated. So, too, inasmuch as the bars 11 extend the full length of the window frame from top to bottom, they not only serve to guide the sashes and yieldably hold them in different raised positions, but, further, function efficiently as weather strips or guards.

By pressing the bars 11 inwardly in the channels 12, they are disengaged from the sashes and the latter are thereby readily removable from the window frame for convenience in cleaning the windows and for other purposes.

For convenience in retracting the spring-pressed sash guiding and supporting bars 11, plates 17, having screw threaded central apertures, are embedded in the vertical side members or stiles 10 of the window frame between the channels 12 in which said bars 11 are mounted. These plates 17 are seated

flush with the face of the frame member or stile 10, and are secured in place by ordinary wood screws 18, the central screw threaded aperture of the plates registering with recesses 19 provided in the frame member or stile 10 to afford clearance for the inner end of an actuating screw 20, which latter is passed through an aperture 21 in a spanner member or plate 22 of a width sufficient to 10 marginally overlap the parallel pair of sash guiding and supporting bars 11, as best shown in Figs. 3 and 4 of the drawing. The screw 20 is provided with a fixed collar 23 affording an annular shoulder which bears against 15 the outer face of the spanner member or plate 22, said screw being further provided at its outer end with a suitable handle 24 by which it is conveniently rotated. By turning the screw in one direction in the central aperture 20 of the plate 17, the spanner member or plate 22 is forcibly moved toward the frame member or stile 10, and presses the guide members or bars 11 inwardly in the channels 12. The plate 22, as shown more clearly in Figs. 2 25 and 4, has its upper end portion flanged, as at 25, so as to afford a ledge or shelf on which the lower edge portions of the sashes 6 and 7 are supported when the guiding and supporting bars 11 are released from their oper- 30 able engagement with said sashes.

The supporting shelf 25 serves as a safety stop for limiting the drop of the sashes when the bars 11 are released, as just above set forth, thereby preventing the sash from becoming damaged and also preventing injury to the operator while manipulating the screw 20 in the act of releasing said guiding and supporting bars 11. The spanner members 22', which are provided for retracting the 40 upper end portions of the sash guiding and supporting bars 11, are relatively narrower than the lower plates 22, as the upper plates have no function to perform other than to straddle the parallel pair of bars 11. The 45 form and arrangement of the upper operating screws is identical with that of the screws as shown and described in connection with the lower plates.

Normally, the spanner plates 22 and 22' 50 are removed from the window frame so as not to interfere with the vertically slidable movement of the sashes on their respective guiding and supporting bars 11. However, when it is desired to remove the sashes from the window frame, the upper sash is preliminarily lowered and the lower sash raised so that access may be had to the upper and lower socket plates 17, to which the actuating screws 20 are applied for the purpose of retracting 55 the guiding and supporting bars 11.

Obviously, the structure admits of considerable modification without in the least departing from the spirit and scope of the invention as defined by the appended claims. 60 The invention, therefore, is not limited to the

specific construction and arrangement shown.

Having thus described our invention, what we claim as new and desire to secure by Letters Patent is:

1. In a window construction, a frame having a vertical side member in which a sash is slidably mounted, a spring-pressed guide element on said vertical frame member normally projecting in engagement with the sash whereby to guide the latter and yieldably support it in raised position, and means external of the frame for retracting said guide element to release it from operable engagement with the sash, said means comprising a plate having a shoulder portion for arresting the sash in its dropping movement after the release of said guide element. 70

2. In a window construction, a frame having a vertical side member having a slideway in which a sash is slidably mounted, a spring-pressed guide element on said vertical frame member normally projected beyond the face of the slideway to engage the sash whereby to guide the latter and yieldably support it in raised position, and means for retracting said guide element and releasing it from operable engagement with the sash, said means comprising a supporting element located on the window frame contiguous to the slideway for the sash, and a detachable element operably engageable with said supporting element and engageable with said guide element whereby to retract the latter and release it from operable engagement with the sash. 80

3. In a window construction, a frame having a vertical side member having a slideway in which a sash is slidably mounted, a spring-pressed guide element on said vertical frame member normally projected beyond the face of the slideway and engaging the sash whereby to guide the latter and yieldably support it in raised position, and means for retracting said guide element and releasing it from operable engagement with the sash, said means comprising a supporting element located on the window frame contiguous to the slideway for the sash, and a detachable element operably engageable with said supporting element, said detachable element carrying a member adapted to depress said guide element and arranged to arrest the dropping movement of the sash when the guide element is released from engagement therewith. 100

4. In a window construction, a frame having a vertical side member having sash slideways, provided with parallel spring-pressed guide bars extending the length thereof, upper and lower sashes respectively slidably engaged with said guide elements whereby to be guided in their movement and yieldably supported in raised position, and means for retracting said guide elements comprising a socket plate located on the vertical side member of the window frame flush with the faces of the sash slideways between the parallel 110 115 120 125 130

pair of spring-pressed guide elements, and a detachable actuating member operably engageable with said socket plate, said actuating member carrying a spanner plate to straddle and engage said parallel spring-pressed guide bars whereby the latter are depressed by the manipulation of said actuating member.

In testimony whereof we have signed our
10 names to this specification.
